(57) **CLAIM**

The ornamental design for a display screen with graphical user interface as shown and described.

DESCRIPTION

FIG. 1 is a front view of a display screen with graphical user interface according to the design; and,
 FIG. 2 is a partially enlarged view thereof along the lines 2-2 and 2'-2' of FIG. 1.

The outermost broken line rectangle in FIG. 1 illustrates the display screen. The remaining broken lines, including all text shown, illustrate portions of the graphical user interface. None of the broken lines form part of the claimed design.
